US00D625545S

(12) **United States Design Patent**
McLemore et al.

(10) **Patent No.:** **US D625,545 S**
(45) **Date of Patent:** **** Oct. 19, 2010**

(54) **COOKING APPARATUS**

(75) Inventors: **Don McLemore**, Fortson, GA (US);
John D. McLemore, Forston, GA (US);
Adam Carter, Auburn, AL (US); **James R. Carden**, Columbus, GA (US)

(73) Assignee: **Masterbuilt Manufacturing, Inc.**,
Columbus, GA (US)

(**) Term: **14 Years**

(21) Appl. No.: **29/345,084**

(22) Filed: **Oct. 9, 2009**
